BICYCLE PEDAL

Donald J. Schrum, South Bend, Ind., assignor to American Safety Equipment Corporation, New York, N.Y., a corporation of New York

Filed Apr. 9, 1965, Ser. No. 84,702

Term of patent 14 years

(Cl. D90—14)

FIG. 1.

FIG. 2.

FIG. 3.

FIG. 4.

FIG. 1 is a top plan view of a bicycle pedal embodying the new design;

FIG. 2 is a side elevation of the same, both sides thereof being similar;

FIG. 3 is one end elevation of the bicycle pedal; and

FIG. 4 is the opposite end elevation of the same.

I claim:

The ornamental design for a bicycle pedal, substantially as shown and described.
